UNITED STATES PATENT OFFICE.

WALTER H. WALKER, OF SEATTLE, WASHINGTON.

CHECK-CONTROLLED APPARATUS FOR VENDING-MACHINES.

1,184,596.

Specification of Letters Patent.

Patented May 23, 1916.

Application filed November 6, 1915. Serial No. 60,113.

To all whom it may concern:

Be it known that I, WALTER H. WALKER, a citizen of the United States, residing at Seattle, in the county of King and State of Washington, have invented new and useful Improvements in Check-Control Apparatus for Vending-Machines, of which the following is a specification.

This invention relates to improvements in check control apparatus for vending machines, change-making machines, etc.

In carrying out the present invention, it is my purpose to provide check controlled apparatus of the class described which will embrace the desired features of simplicity, efficiency and durability, which will operate effectively when a coin of the proper denomination has been deposited therein and wherein the component parts will be so arranged and correlated as to reduce the possibility of derangement to the minimum.

With the above recited objects in view and others of a similar nature, the invention consists in the construction, combination and arrangement of parts set forth in and falling within the scope of the appended claim.

In the accompanying drawings:—Figure 1 is a view in front elevation of a vending machine equipped with check controlled apparatus constructed in accordance with the present invention. Fig. 2 is a longitudinal vertical sectional view therethrough. Fig. 3 is an enlarged sectional view in the line 3—3 of Fig. 2. Fig. 4 is a similar view on the line 4—4 of Fig. 2. Fig. 5 is a like view on the line 5—5 of Fig. 2. Fig. 6 is a longitudinal sectional view through the coin controlled mechanism showing the parts on an enlarged scale.

Referring now to the drawings in detail, 1 designates a casing constructed of suitable material and having the front wall thereof formed with a coin slot 2, an opening 3 below the coin slot 2 and an opening 4 below 45 the opening 3. Secured to the front wall of the casing below the opening 4 and projecting outwardly from such wall is a shelf 5 adapted to support a cup 6 or other vessel.

Secured to the inner surface of one side 50 wall of the casing 1 is a supporting plate 7 and secured to the supporting plate 7 and projecting outwardly therefrom is a horizontal guide plate 8 having an outer edge formed with an upturned flange 9 coöperating 55 with the confronting portion of the plate 7 to form a guideway. Mounted upon

the guide plate 8 within the way formed by the flange 9 and the adjacent portion of the supporting plate 7 is a bar 10 capable of longitudinal sliding movement upon the 60 plate 8 and having the forward end portion formed with an upwardly projecting lip 11 and the rear end bifurcated as at 12. Mounted upon the forward end portion of the bar 10 and capable of sliding movement thereon 65 is the inner end portion of a plunger 13, such plunger having the outer end thereof projecting through the opening 3. Surrounding the plunger 13 and spaced apart from the forward end of the supporting plate 7 70 is a collar 14 and encircling the plunger between the collar 14 and the adjacent end of the plate 7 is a coiled expansion spring 15 acting to hold the forward end of the plunger 13 normally projected through the opening 3. Formed on the lower edge of the plunger 13 at the inner end thereof is a shoulder 16 designed to abut the lip 11 to limit the outward movement of the plunger under the action of the spring. The inner 80 end of the plunger is also formed with a coin slot 17 that normally registers with a similar slot 18 formed in the bar 10 and leading from the coin slot 2 in the front wall of the casing 1 to the slot 17 in the 85 plunger is a coin chute 19 whereby coins may be conveyed from the slot 2 into the normally registering slots 17 and 18 to connect the plunger 13 to the bar 10. When the alining coin slots 17 and 18 are unoccupied by a coin, the plunger 13 may be pressed inwardly against the action of the spring 15 without influencing the bar 10 and in this inward movement of the plunger the inner 90 end thereof slides over the outer end portion 95 of the bar. When, however, the coin is deposited in the slot 2 such coin slides down the chute 19 into the registering slots in the plunger and bar, thereby forming a connection between the plunger and the bar so that 100 in the inward movement of the plunger the bar will be likewise actuated upon the guide plate 8. The upper surface of the guide plate 8 is preferably formed with a channel 20 below the slot 18 in the bar and disposed 105 contiguous to the rear end of the channel 20 is a discharge slot 21. As the plunger and bar move rearwardly incident to the coin connecting the same, the lower edge of the coin slides along the channel 20 and the slots 110 17 and 18 move into registration with the discharge slot 21 in the guide plate 8, there-

by releasing the coin and permitting the latter to fall into a receptacle on the bottom wall of the casing. As soon as the coin falls out of the slots 17 and 18, the bar 10 is relieved of the influence of the plunger 13 and when the plunger is released the spring 15 coacts to restore the same to normal position. When the plunger is moved into normal position the shoulder 16 in engagement 5 with the lip 11 on the bar 10 slides the latter over the guide plate 8 to normal position so that the above cycle of operation may be repeated when another coin of the proper denomination is deposited in the slot 2.

15 In the present instance, I have shown my improved check controlled apparatus as used in connection with a coffee dispensing machine, such machine comprising an outer receptacle 22 and an inner receptacle 23 arranged within the upper portion of the outer receptacle. The receptacle 23 is adapted to contain the coffee to be dispensed and has the lower end thereof equipped with an outlet 24 connected to a suitable form of cut 20 off valve 25 which in turn communicates with a measuring chamber 26 having the lower end thereof provided with a cut off valve 27 and from the cut off valve 27 leads a discharge spout 28 extending through the 25 opening 4 in the front wall of the casing 1 and adapted to discharge the coffee to the vessel 6 on the shelf 5.

29 indicates a lever fulcrumed between its 30 ends upon the supporting plate 7 and having the upper portion thereof connected with the bifurcated end 12 of the bar 10. The upper end of the lever 9 is connected with the stem of the valve 25 while the lower end of such lever is connected with the stem 35 of the valve 27. The valve 25 is normally opened so that the coffee may flow from the receptacle 23 into the measuring chamber 26, while the valve 27 is normally closed to cut off communication between the measuring 40 chamber and the discharge spout. The lower portion of the receptacle 22 contains a quantity of hot water or other heating medium so as to heat the contents of the measuring chamber 26. These receptacles 45 23 and 22 are provided with suitable drain cocks and catch glasses as illustrated in Fig. 2 of the drawings, while the measuring chamber 26 is provided with a vent pipe 30 to facilitate the discharge of the coffee therefrom when the lower valve 27 is opened and the upper valve closed.

50 In practice, when the coin has been de-

posited in the slots 17 and 18, and the bar 10 moved inwardly under the action of the plunger 13, such bar swings the lever 29 60 about its fulcrum thereby closing the valve 25 and opening the valve 27 to cut off communication between the receptacle 23 and the measuring chamber and dispense the coffee in the measuring chamber. When the 65 coin is discharged through the slot 21 and the plunger released the spring 15 coacts and restores the valves 25 and 27 to normal positions.

While I have herein shown and described 70 one preferred form of my invention, by way of illustration, I wish it to be understood that I do not confine myself to the precise details of construction herein described, and delineated, modifications and variations may 75 be made within the scope of the claim and without departing from the spirit of the invention.

I claim:—

In check controlled apparatus for vending 80 machines, a bar capable of sliding movement and having a lip formed on the upper surface thereof at one end, and a vertical slot formed therein and spaced apart from said lip, a plunger having one end portion 85 thereof slidably mounted upon the lip and said bar and formed with a shoulder normally engaging said lip and with a vertical coin slot normally registering with the slot in said bar whereby the coin deposited in 90 said slots may form a connection between the plunger and the bar, a spring surrounding said plunger and acting thereon to hold the same in normal position and to restore the same and the bar to normal position succeeding the operation thereof, and a horizontal guide plate supporting said bar and having the upper surface thereof formed with a channel below the slot in said bar, said channel communicating at one end with the 100 slot in said bar and at its opposite end with a vertical slot formed in said guide plate, the last-mentioned slot being adapted to register with the first-mentioned slots in the sliding movement of the plunger and the bar 105 whereby the coin will be released from said first-mentioned slots.

In testimony whereof I affix my signature in presence of two witnesses.

WALTER H. WALKER.
